ATTORNEY

UNITED STATES PATENT OFFICE.

ALVIN R. BURDICK, OF AURORA, ILLINOIS.

TICKET-CASE.

SPECIFICATION forming part of Letters Patent No. 292,789, dated February 5, 1884.

Application filed June 8, 1883. (No model.)

To all whom it may concern:

Be it known that I, ALVIN R. BURDICK, of Aurora, in the county of Kane and State of Illinois, have invented new and useful Improvements in Ticket-Cases, of which the following is a specification, reference being had to the accompanying drawings, illustrating the improvement, in which—

Figure 1 is a perspective representation of a ticket-case embodying my improvements; Fig. 2, a longitudinal perspective view of the same; Fig. 3, a cross-section of Fig. 1 on line *x*.

The present invention relates to an improvement in that class of ticket or card cases in which the tickets or cards are held to the top of the case by a platen and spring, that they may be drawn out one at a time from the end of the case, the spring forcing the bunch of tickets or cards up, so as to take the place of the one drawn out. The especial improvement is the novel formation of the flanges on the upper part of the sides of the box, which permit of the tickets being inserted through the top of the box by means of the cover, and prevent them from being forced out by the spring and platen.

I know that stamp-holders have been made with ends and sides complete, and provided with flanges, to hold the stamps in the box—such as the stamp-holder patented to Phidello W. Hall, May 11, 1875, No. 164,833, where the flanges are cut off, so as to leave a space for the insertion of the stamps. To introduce a sufficient number of stamps into the holder to fill it, they would have to be considerably bent, and, being flexible, this can be readily done; but it would be impracticable to insert ordinary tickets or cards therein, because they are comparatively inflexible, and could not be sufficiently bent. I also know that ticket-cases have been made with flanges on their sides, wherein the tickets are inserted through a hinged end; but I do not believe that ticket-cases have been made or used which have complete ends and sides which will allow of the tickets or cards being forced between the flanges into the case by means of the cover, as hereinafter more fully described and shown.

The case is made of light metal plate, with a bottom, A, cover B, sides J, and ends C D.

The end C is less in height than the end D and sides J, that the tickets may be drawn out from under the cover B. Flanges F are formed by bending the upper middle portions of sides J slightly inward, and their purpose is both to hold the cards in the case and to admit the cards to be put in a body into the case through the top thereof. The advantage of this is that the expense of a hinged part is obviated, and the saving of time of putting the cards endwise and singly in the case where the ends are closed. The spring G, riveted to the under side of the platen H, is of such form and strength as to lie flat, or nearly so, on the bottom A when the case is full of tickets, and will hold the tickets up to the flanges, to be removed from the box.

To insert the cards and tickets, they are placed on the upper part of the flanges F, (the cover being raised.) The cover B is then closed, to force the tickets between the flanges and into the case; or the requisite number of tickets may be placed on the under side of the cover, and forced into the box by the closing of the cover. In either case it will be observed that the tickets or cards are not forced flatly or bodily past the flanges into the box; but, instead thereof, the ends of the cards nearest to the hinge of the cover are first forced between them. No inconsiderable friction on the edges of the cards is attained by thus placing them in the box, for the reason that the flanges are very narrow and extend only over the middle portions of the sides J, whereby the latter may spring slightly outward by the contact of the cards with the flanges. It will be observed that where the cards commence to enter the box near the hinge to the cover there are no flanges; hence the cards, when placed against the cover, fall between the sides of the box at the hinged end by the partial closing of the cover, and are thus in positions to be forced between the flanges by the further shutting of the cover. In other words, the cards commence entering the box in a diagonal position, and are made to lie flat in the box by the shutting of the cover.

I claim as new and desire to secure by Letters Patent—

A ticket or card case composed of solid ends, 100

bottom, and sides, and a hinged cover, one end of the box being made narrower for withdrawing the cards, and the middle portions of the tops of the sides provided with 5 narrow inwardly-turned flanges F, with spaces between the flanges and the hinged end of the cover, whereby cards placed on the under side of the cover will at their ends pass between

the sides of the box, and be forced past the flanges, and lie flat in the box, by the shutting 10 of the cover, as specified.

ALVIN R. BURDICK.
